UNITED STATES PATENT OFFICE.

NICASIO STANFA, OF BEAUMONT, TEXAS.

DESIGN FOR A BRAKE.

53,618.

Specification for Design.

Patented July 15, 1919.

Application filed September 27, 1918. Serial No. 255,981. Term of patent 14 years.

To all whom it may concern:

Be it known that I, NICASIO STANFA, a citizen of the United States, residing at Beaumont, in the county of Jefferson and State of Texas, have invented a new, original, and ornamental Design for a Brake, of which the following is a specification, reference being had to the accompanying drawings, forming a part thereof.

Figure 1 is a perspective view, Fig. 2 is a bottom plan view and Fig. 3 is an elevation.

I claim:

The ornamental design for a brake, as shown.

NICASIO STANFA.
